ARTICLE ATTACHING MACHINE

Joseph Vollman, Elizabeth, N. J., assignor to The
Singer Manufacturing Company, Elizabeth,
N. J., a corporation of New Jersey

Application June 25, 1948, Serial No. 35,121

11 Claims. (Cl. 112—110)

1 This invention relates to article attaching machines such, for example, as those used for attaching buttons to articles of wearing apparel.

More specifically stated, the invention relates to article attaching machines of the lock-stitch variety having automatic thread-cutting means, and it has, as its primary object, to provide, in this type of machine, means for automatically lowering the button-clamp, and the button held therein, upon the workpiece at the beginning of a sewing cycle and for automatically raising the clamp, to release the workpiece, at the completion of the sewing cycle, without leaving any objectionably long thread ends at the under side of the workpiece.

Lock-stitch button-sewing machines of the type disclosed in this application are old and well known, being recognized in the trade as the Singer Class 69 machines. A generally similar machine is illustrated in United States patent of A. F. Fifield, No. 1,529,020, March 10, 1925. This type of machine is commonly provided with automatically actuated means for cutting the needle and bobbin threads at the completion of the article attaching cycle; the thread-cutting means being actuated by the overthrow of the machine after the stop-motion has been actuated to bring the machine to rest. Thread-cutting mechanisms of this nature are disclosed in United States patents of C. M. Horton, No. 807,676, December 19, 1905, A. F. Fifield, No. 1,442,141, January 16, 1923 and J. Vollman, No. 1,999,145, April 23, 1935.

An automatic clamp lowering and raising mechanism of the type disclosed in this application forms the subject of United States patent of M. McCann, No. 2,300,585, November 3, 1942. The button-sewing machine disclosed in that patent, however, is of the single-thread chain-stitch variety and the upward movement of the clamp is utilized to break the needle thread, a loop of which is held by the looper at the end of the sewing cycle.

In lock-stitch button-sewing machines, as heretofore constructed, it is impracticable to sever the needle and bobbin threads by the lifting of the button-clamp, as those threads are not held against endwise movement and consequently raising of the button-clamp merely acts to draw off needle and bobbin thread without breaking either thread. Therefore, in lock-stitch button-sewing machines mechanical thread-cutting means are essential.

Attempts to embody the automatic clamp-lifting means of the McCann Patent No. 2,300,585 in lock-stitch button-sewing machines having

2 automatic thread-cutting means, such as disclosed in the above mentioned Fifield and Vollman patents, were unsuccessful due to the fact that the clamp was lifted by the last upstroke of the needle-bar before the machine came to rest, whereas the threads were cut by the overthrow of the machine after the clamp, the workpiece and the button attached thereto had been raised. This caused objectionably long thread ends to be left at the under side of the workpiece, which thread ends later had to be removed manually.

This invention therefore has as another object to provide an improved work-clamp which may be combined with automatic clamp-lifting and lowering means and mechanical thread-cutting means and which will obviate the leaving of objectionably long thread ends at the under side of the workpiece.

With the above and other objects in view, as **20** will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a side elevation of a **30** lock-stitch button-sewing machine embodying the present invention.

Fig. 2 is a detail perspective view of the automatic means for causing the reciprocating needle-bar to raise and lower the button-clamp.

Fig. 3 is an under side view of the throat-plate **35** of the machine and the mechanical thread-cutting mechanism carried thereby which is actuated by the overthrow of the machine after the stop-motion mechanism has substantially arrested the action of the machine, the parts being shown substantially in the positions which they occupy when the machine comes to rest.

Fig. 4 is a plan view of the forward portion of **45** an improved button-clamp which is used in combination with the automatic clamp-lifting means and the automatic thread-cutting mechanism.

Figs. 5 and 6 are bottom and side views, respectively, of the clamp shown in Fig. 4.

Fig. 7 is a right end view of the improved button-clamp.

Fig. 8 is a fragmentary end view of the clamp, showing portions thereof lifted by the automatic clamp-lifting means and other portions thereof holding a button attached to a workpiece and held down by the pull of the threads, prior to the cutting of the threads.

Referring more specifically to the drawings, the invention is disclosed as embodied in a "Singer Class 69" button-sewing machine comprising a frame including a base 1, a work-supporting bed 2, a standard 3, and an over-hanging bracket-arm 4 which terminates in a bracket-arm head 5. Journaled lengthwise within the arm 4 is a main or driving shaft 6, having on its rear end a fast pulley F, adapted to be driven by a suitable power belt, not shown, and a loose pulley L on which the belt runs when the machine is at rest. A conventional stop-motion mechanism, designated generally as 7, controls the running and stopping of the machine and the actuation of a suitable thread-cutter herein-after referred to, in the manner disclosed in said United States patent of C. M. Horton, No. 807,676, December 19, 1905.

Mounted for endwise reciprocation in the bracket-arm head 5 is a needle-bar 8 which carries, at its lower end, an eye-pointed thread-carrying needle 9. The needle-bar is reciprocated from the main shaft 6, by a conventional crank-disk 10 and a link 11 which connects a crank-pin 12, carried by the crank-disk, with a collar 13 secured upon the needle-bar. Cooperating with the needle 9, in the formation of stitches, is a loop-taker T of the oscillating shuttle lock-stitch type. This loop-taker carries a bobbin or lower thread t which, during the stitch-forming cycle, is concatenated with an upper thread n carried by the needle (Fig. 8).

Secured to the upper side of the free end of the work-supporting bed 2 is a throat-plate 14 which carries, at its under side, an automatically actuated thread-cutting mechanism (Fig. 3) including a bobbin-thread pull-off blade a, a needle-thread pull-off blade b, a stationary cutter-blade c and a cooperating needle-thread cutting-edge d carried by the blade b. The bobbin thread is cut by a vertically disposed cutting edge shown in dotted lines in Fig. 3 and designated as e. This thread-cutting mechanism also includes a needle-thread nipper-blade f which grips the free end of the needle-thread between the blade f and the under side of the throat-plate; adjacent a needle-hole h in the throat-plate, and holds it during the formation of the first three stitches of each sewing cycle to insure the proper formation of the stitches and to prevent unthreading of the needle. As hereinbefore stated, this thread-cutting and -nipping mechanism is similar in construction and operation to those disclosed in the above mentioned United States patents of C. M. Horton, A. F. Fifield and J. Vollman.

The thread pull-off, -cutting and -nipping blades are secured upon an arm 15 journaled upon a stud 16 carried by a bracket 17 secured to the under side of the throat-plate. The arm 15 is fixed to and oscillated by a segmental pinion 18 engaged by the teeth of a rack 19. This rack is carried by the forward end of a slide-bar 20. At its rear end, the slide-bar 20 carries a stud or roller 72, which is engaged by the forked arm 73 of a bell-crank lever, the other arm 74 of which carries a pin 75 which is connected with and operated by the lower end of the stop-motion lever 7, as explained in said Horton Patent No. 807,676.

Mounted upon the upper surface of the work-supporting bed 2, and reciprocated horizontally in transverse directions from suitable cam grooves formed in a rotary cam-disk D, as described in said Horton patent, is a button-clamp designated generally as C. This clamp comprises a slide-bar 21 which carries, at one end, a work-support-

ing plate 22 upon which the work is held. Overlying the bar 21 is a supporting arm 23 which has its rear end pivotally mounted in a block 24 secured upon the bar 21. A leaf-spring 25, also secured to the block 24, normally tends to depress the forward free end of the arm 23 and the parts carried thereby. Secured to the forward end of the arm 23 is a substantially C-shaped lifting bracket 50 adapted to receive a roller or stud 51 carried by an arm 52 secured upon the lower end of a clamp-lifting rod 53 slidably mounted in the bracket-arm head 5.

Means, generally similar to that shown in United States patent of McCann, No. 2,300,585, November 3, 1942, is provided for automatically lowering the button-clamp by the first down-stroke of the needle-bar and for automatically lifting the clamp by the final upstroke of the needle-bar, during each sewing cycle. This means (see Fig. 2) comprises an abutment member 54 journaled on the clamp-lifting rod 53 at opposite sides of a pinch-collar 55 secured upon said rod. The abutment member has an actuating arm 56 projecting from one side thereof and an abutment finger 57 projecting from the opposite side thereof and adapted, at certain times, to be swung above and into the path of movement of the collar 13 on the needle-bar 8. Secured to and projecting upwardly from the arm 56, is a pin 58 upon which is slidably fitted, for relative vertical movement, the flattened and perforated end portion 59a of a push-pull rod 59. This rod has its forward end slidably mounted in a bore in the bracket-arm head and at its opposite end in a bearing formed in a bracket 60 secured upon the side of the arm 4. A coil spring 60a, surrounding the rod 59 between a washer 61 loose on the rod and a collar 62 secured to the rod, normally urges the rod rearwardly, thereby swinging the abutment member 54 on the rod 53 to a position in which the finger 57 is out of the path of reciprocation of the collar 13. The washer 61 abuts against the curved side of the arm 4 and is thereby held against movement to the right as seen in Fig. 1. A stop 63 on the rear end portion of the rod 59 is adapted to engage the side of the bracket 60 to limit the rearward movement of the rod.

Secured, at diametrically opposite points, on the cam disk D (which is driven from the shaft 6 and designed to be rotated 180° degrees for each complete button-sewing cycle) are two cam-blocks 64; each having a leading cam-edge 64a and a trailing cam-edge 64b.

During the operation of the machine and specifically during the last downstroke of the needle-bar in a button-sewing operation, one of the cam-surfaces 64a engages the rear end of the push-pull rod 59 and causes it to be moved forwardly in opposition to the spring 60a. This movement of the rod swings the abutment member 54 to the position shown in Fig. 2 in which the abutment finger 57 is arranged above and in the path of movement of the collar 13 on the needle-bar. As the needle approaches its uppermost position, on its final upstroke, the collar 13 engages the under side of the finger 57, thereby lifting the abutment member 54, which, in turn, lifts the rod 53, arm 52 and finally the bar 23 of the button-clamp and certain ones of the parts carried thereby.

Upon starting the machine for the next cycle of operation, the initial portion of the first downward movement of the needle-bar is accompanied by a similar downward movement of the abut-

ment member 54, the rod 53 and the button-clamp, to place a new button on the work. Before the collar 13 has reached the level of the abutment finger 57, in the first upstroke of the needle-bar, the cam-block 64 passes from beneath the end of the rod 59 and the spring 60^a shifts the rod rearwardly, thereby swinging the abutment member 54 clockwise, as viewed in plan. This removes the abutment finger 57 from the path of movement of the collar 13 on the needle-bar which may then be reciprocated, without affecting the clamp-lifting mechanism, until the last upstroke of the needle-bar, as above described.

As explained in said McCann Patent No. 2,300,585, in single-thread chain-stitch button-sewing machines the upward movement of the button-clamp is used to sever the sewing thread. As above stated the threads of a two-thread lock-stitch button-sewing machine cannot be broken by merely lifting the button-clamp, it being necessary to employ mechanically actuated knives for severing the needle and bobbin threads and for nipping the needle thread to insure starting of the next sewing cycle. It was found that when applying the automatic clamp-lifting means to a two-thread lock-stitch machine, in which the thread-cutters were actuated by the overthrow of the machine after the last upstroke of the needle-bar, the button-clamp and the button B held therein (which had then been attached to the workpiece W) would be lifted above the work-supporting plate of the clamp with relatively long threads depending below the work and surrounding the thread pull-off blades. When the thread-cutters were actuated, by the overthrow of the machine, they would sever the threads below the under side of the throat-plate, thereby leaving objectionably long thread-ends projecting from the under side of the work, which thread-ends had to be removed manually.

I finally conceived the idea of combining with the automatic clamp-lifting means and the mechanically actuated thread-cutting means a novel form of button-clamp which permits the major portion of the button-clamp to be raised by the last upstroke of the needle but which permits the button and the workpiece to retain their positions relative to the stitch-forming and thread-cutting mechanisms until after the thread-cutting mechanism has been actuated to sever the threads close to the under side of the workpiece, after which the remaining portion of the work-clamp and the button and the workpiece attached thereto also are raised automatically to permit removal of the workpiece with its attached button and the insertion of a new workpiece and another button.

The improved button-clamp comprises, in addition to the bar 21, work-supporting plate 22 and arm 23, hereinbefore mentioned, a pair of presser-members 26 and 27 pivotally mounted at x on the arm 23 and having, at their forward ends, opposed presser-feet 26^a and 27^a, respectively. The forward ends of the arms 26 and 27 are normally urged toward each other by the action of a coil spring 28 having one end fastened to a screw 29, threaded into the arm 23, and its other end connected to a screw 30 threaded into a bar 31, slidably mounted in a slot 32 formed in the supporting arm 23. Attached to the under side of the bar 31 is a slide-plate 33 having converging slots 34 and down-turned thumb-pieces 35. Pins 36 projecting downwardly from the arms 26 and 27 enter the slots 34, whereby rearward movement of the slide-plate 33 causes the arms 26 and 27 to be separated, in opposition to the spring 28. An

adjustable lever 37, fulcrumed on a screw 38 and held in adjusted positions by a clamp screw 39, serves as an abutment for the screw 39 to limit the closing of the presser-arms 26, 27. The forward end 31^a of the bar 31 is turned down and has a portion 31^b which overlies a button held between suitable clamp jaws, later to be described, to prevent upward movement of the rear edge of the button. Also secured to the under side of the slide-bar 31, by a screw 40, is a sheet metal arm 41 which has its forward end portion 41^a underlying the portion 31^a of the bar 31. The end portion 41^a is formed with diverging walls 41^b which serve as an abutment to limit the inward movement of the button when it is inserted into the clamp jaws.

In button-clamps as heretofore constructed, the buttons were supported and clamped by jaws provided by arms generally similar to the above mentioned arms 26 and 27 and therefore lifting of the supporting arm 23 effected lifting of the button.

In the present improved clamp the buttons are supported and clamped wholly independently of the arms 26 and 27 thereby permitting the major portion of the button-clamp to be raised automatically during the final upward movement of the needle-bar without raising the work W or the button B which are held depressed by the loop of needle thread which is then held by the loop-taker L. Secured to the under side of the arms 26 and 27, at the rear ends thereof, by screws 42, are two spring arms 43 and 44, respectively. Each of the arms 43 and 44 extends forwardly and downwardly and provides, beneath the presser-feet 26^a and 27^a, a horizontally disposed work-depressing and button-supporting seat 45. The arms 43 and 44 also carry upwardly inclined and rearwardly diverging button-gripping jaws 46 which normally engage and are pressed downwardly by the presser-feet 26^a and 27^a. The jaws 46 and the flange 41^b afford between them a button-locating cavity, the walls of which have a three-point contact with the buttons. The rearward divergence of the jaws 46 tends to force the buttons inwardly into contact with the abutment flange 41^b. A metal strap member 47, secured to the spring arm 43 by a screw 48, has a loop portion 47^a which slidably engages the spring arm 44. This strap member 47 holds the arms 43 and 44 against relative vertical movement but permits relative horizontal movement therebetween. The strap member 47 has a raised mid-portion 47^b which overlies the forward down-turned portion 31^a of the arm 31 and which permits raising of that arm with the presser-arms 26 and 27 relative to the arms 43 and 44. A thin plate 49 secured to the under side of the arm 41 underlies the spring arms 43 and 44 and prevents relative vertical movement between those three arms.

From the foregoing, it will be apparent that this invention has combined in a lock-stitch button-sewing machine having an automatically actuated thread-cutter and an automatic clamp-actuating mechanism adapted to lower the button-clamp by the first downstroke of the needle-bar and to raise the major portion of the button-clamp by the last upstroke of the needle-bar, in each sewing cycle. It will also be apparent that this invention has combined with the automatic thread-cutting and clamp-actuating means an improved form of button-clamp which permits the major portion of the clamp to be lifted before the needle thread n and the bobbin thread t

have been severed and without disturbing the normal relationship between the work, the button and the thread-cutting mechanism, whereby the threads are cut close to the under side of the work, after which the work and its attached button also are raised above the work-support.

Having thus set forth the nature of the invention, what I claim herein is:

1. An article attaching machine having, in combination, a frame; stitch-forming mechanism carried by said frame and including a reciprocating needle-bar, a thread-carrying needle secured in said needle-bar, and a thread-carrying loop-taker cooperating with said needle in the formation of lock-stitches; an article-holding clamp mounted on said frame and movable vertically relative thereto, said clamp comprising two relatively movable portions, one an article-holding portion adapted to hold an article in the path of reciprocation of the needle and the other a presser portion adapted to press the article-holding portion upon an underlying workpiece; thread-cutting means located between said loop-taker and said clamp; means actuated by the final upstroke of the needle-bar in a sewing cycle to lift the presser portion of the clamp relative to the article-holding portion; and means thereafter to actuate said thread-cutting means to cause it to sever the sewing threads close to the under side of the workpiece.

2. An article attaching machine having, in combination, a frame; stitch-forming mechanism carried by said frame and including a reciprocating needle-bar, a thread-carrying needle secured in said needle-bar, and a thread-carrying loop-taker cooperating with said needle in the formation of lock-stitches; an article-holding clamp mounted on said frame and movable vertically relative thereto, said clamp comprising two relatively movable portions, one an article-holding portion adapted to hold an article in the path of reciprocation of the needle and the other a presser portion adapted to press the article-holding portion upon an underlying workpiece; thread-cutting means located between said loop-taker and said clamp; automatic means actuated at the end of the sewing cycle to lift the presser portion of the clamp while said article-holding portion is held depressed by the sewing thread; and means thereafter to actuate said thread-cutting means to cause it to sever the sewing threads close to the under side of the workpiece.

3. An article attaching machine having, in combination, a frame; stitch-forming mechanism carried by said frame and including a reciprocating needle-bar, a thread-carrying needle secured in said needle-bar, and a thread-carrying loop-taker cooperating with said needle in the formation of lock-stitches; an article-holding clamp mounted on said frame and movable vertically relative thereto, said clamp comprising two relatively movable portions, one an article-holding portion adapted to hold an article in the path of reciprocation of the needle and the other a pair of presser elements adapted to press the article-holding portion upon an underlying workpiece, said article-holding portion comprising a pair of spring arms secured to the under side of said presser elements, said spring arms carrying article-supporting plates and opposed article-clamping jaws; thread-cutting means located below said article holding clamp; means actuated by the final upstroke of the needle-bar in a sewing cycle to lift the presser elements of the clamp relative to the article-holding portion while said

article-holding portion is held depressed by the sewing threads; and means thereafter to actuate said thread-cutting means to cause it to sever the sewing threads close to the under side of the workpiece.

4. An article attaching machine as set forth in claim 3 in which the presser elements are pivotally mounted for oppositely directed horizontal movements; in which the spring arms are secured to the presser elements for horizontal movements therewith; and in which means is provided for preventing relative vertical movement between said spring arms.

5. An article attaching machine as set forth in claim 3 in which the presser elements are pivotally mounted for oppositely directed horizontal movements; in which the spring arms are secured to the presser elements for horizontal movements therewith; and in which a member secured to one of said spring arms has a loop portion slidingly engaging the other spring arm to permit relative horizontal movements between said arms but to prevent relative vertical movement therebetween.

6. An article attaching machine having, in combination, a frame; a rotary shaft journaled therein; stitch forming mechanism carried by said frame and including a reciprocating needle-bar actuated from said shaft, a thread-carrying needle secured in said needle-bar, and a thread-carrying loop-taker cooperating with said needle in the formation of lock-stitches; an automatically actuated stop-motion device to control the rotation of said shaft; an article-holding clamp mounted on said frame and movable vertically relative thereto, said clamp comprising two relatively movable portions, one an article-holding portion adapted to hold an article in the path of reciprocation of the needle and the other a presser portion adapted to press the article-holding portion upon an underlying workpiece; thread-cutting means located below the article-holding portion of said clamp; means actuated by the final upstroke of the needle-bar in a sewing cycle to lift the presser portion of the clamp while said article-holding portion is maintained in contact with the workpiece; and means controlled by said stop-motion device thereafter to actuate said thread-cutting means to cause it to sever the sewing threads close to the under side of the workpiece.

7. In a button attaching machine having a frame; stitch-forming mechanism carried by said frame and including a reciprocating needle-bar, a thread-carrying needle secured in said needle-bar, and a thread-carrying loop-taker cooperating with said needle in the formation of lock-stitches; a work-holding clamp mounted on said frame and movable vertically relative thereto, said clamp comprising a work-supporting plate, a pair of spring arms located above said work-supporting plate and having button-holding jaws adapted to hold a button in the path of movement of the needle, and a pair of spring depressed presser-members located above said spring arms and adapted to press said arms upon a workpiece located on said work-supporting plate.

8. In a button attaching machine having a frame, stitch-forming mechanism carried by said frame and including a reciprocating needle-bar, a thread-carrying needle secured in said needle-bar, and a thread-carrying loop-taker cooperating with said needle in the formation of lock-stitches; a work-holding clamp mounted on said frame and movable vertically relative thereto,

said clamp comprising a work-supporting plate, a pair of spring arms located above said work-supporting plate, said arms having rearwardly diverging and opposed button-holding jaws, a button stop located between said jaws adjacent the rear end thereof, a member secured to one of said arms and embracing the other arm to prevent relative vertical movements between said arms, and a pair of spring-depressed presser members bearing upon said spring arms to press them into clamping contact with a workpiece located on said work-supporting plate.

9. In a button-sewing machine, including stitch-forming mechanism, thread-cutting mechanism, a stop-motion device, and means operated by said stop-motion device for actuating said thread-cutting mechanism to sever the sewing threads, in combination, a button-holding clamp, a presser member, and automatic means for lifting said presser member at the completion of a stitching cycle and prior to the actuation of said thread-cutting mechanism without disturbing the position of the button-holding clamp.

10
20

10. A button clamp for sewing machines, comprising a supporting arm, presser members carried by said arm and having opposed extremities, yielding button-supporting arms carried by said presser members, and a stop located intermediate the opposed extremities of said presser members and having an overhanging button-engaging lip and divergent button-engaging walls.

11. A button clamp for sewing machines, comprising a supporting arm, presser members carried by said arm and having opposed extremities terminating in vertically inclined and rearwardly divergent walls, and yielding button-supporting arms carried by said presser members and terminating in inturned ends having upstanding and rearwardly diverging button-engaging walls and button-supporting ledges disposed between the extremities of said work-pressing members.

JOSEPH VOLLMAN.
